NEEDLE OPERATING MECHANISM FOR
AXMINSTER LOOMSOscar V. Payne, Leicester, Mass., assignor to
Crompton & Knowles Loom Works, Worcester,
Mass., a corporation of Massachusetts

Application October 28, 1940, Serial No. 363,129

15 Claims.

(Cl. 139—124)

This is a continuation in part of my co-pending application Serial No. 293,184 filed September 2, 1939.

This invention relates to improvements in weft needle operating mechanisms more particularly for Axminster looms and it is the general object of the invention to provide light weight actuating means capable of attaining high speeds.

It has been customary heretofore to drive the needles of Axminster looms by means of a drum oscillated by a heavy reciprocating segment gear. The weight of these parts has interfered with efforts to increase the speed of a loom and it is an important object of my present invention to replace the drum and segment gear by a system of stationary and movable pulleys around which is trained a cable connected to the needle operating carriage. Each of the movable pulleys has the effect of doubling the motion of the needle carriage, and by employing a sufficient number of movable pulleys I have been able to operate a needle on a wide loom by mechanism which reciprocates the movable pulleys through a comparatively short distance.

In Axminster looms the weft is derived from an outside stationary support and is laid in the shed by a needle which must enter and leave the shed for each crossing of the harnesses. The harnesses are open sufficiently to receive the needle for approximately seven-twelfths of a loom beat. The needle speed is therefore relatively high since it must traverse the shed twice for each harness crossing, or in slightly more than one-half a second at sixty picks per minute, and any reduction in weight of the needle actuating mechanism facilitates increase in loom speed. Except for slight differences in the friction of the weft passing through the needle eye the work expended in moving the needle in to the shed is substantially the same as that required to move it out of the shed and for this reason the cable already mentioned can be of uniform size throughout its length. This condition also means that the needle inserting and withdrawing parts of the mechanism wear uniformly, and compensation for the wearing of both parts will be substantially the same.

It is a further object of my present invention to employ a cable the ends of which are fixed relatively to each other and the intermediate part of which is connected to a sliding needle carriage, together with a set of movable sheaves so related to the moving cable that the intermediate part of the latter will be caused to move

along the needle rail when the pulleys move to cause a paying-out motion of one end of the cable which is just compensated for by a shortening of the other end of the cable. This result may be accomplished by leading the cable from an anchor around half of the movable pulleys and half of the stationary pulleys and then connecting it to the needle carriage, the remainder of the cable extending from the carriage to be trained around the remaining stationary and movable pulleys and then attached to another anchor. In this way the cable is kept taut throughout the reciprocation of the needle.

10 It is a further object of my present invention to distribute the strains on the movable pulleys in such a way as to effect a balance in the forces acting on the pulley support, thereby avoiding any tendency to twist the latter. If, for instance, three movable sheaves are employed for that part of the cable which inserts the needle into the shed two of them will be relatively near the support of the stud carrying the pulleys while the third will be at a greater distance from the support. In order to accomplish this distribution of strains I employ stationary pulleys which are disposed diagonally so that the top of the stationary pulley will align with the movable pulley on one side of the support while the bottom of the stationary pulley aligns with another movable pulley on the opposite side of the support. This relationship has the further advantage of keeping the cable sections parallel not only with themselves but also with the sheaves, thereby reducing wear of the sheave flanges.

15 It is a further object of my invention to connect the selvage shuttle and movable pulley driving mechanisms so that the shuttle will have an operating motion when the pulleys are at or near that end of their stroke which occurs when the needle is in the warp shed.

It is another object of my invention to provide for tensioning at least one end of the cable sufficiently to keep the cable taut at all times and avoid slipping of the cable on the pulleys, thereby reducing wear of both the cable and pulleys. The yielding of the cable made possible by the tensioning means also avoids shock and abrupt application of force to the carriage and needle, thereby further facilitating operation at high speeds.

20 It is another object of my present invention to mount the pulley system on a structure one side of which is the usual needle rail. In this

way I am able to use an existing part of the needle guiding mechanism to assist in supporting the mechanism which operates the pulleys and cable.

It is a still further object of my present invention to support the movable pulleys on a mounting so controlled that they move in a substantially straight line between the fixed pulleys. This result I accomplish by means of supporting the operating lever for the movable pulleys in such a way that the throw or amplitude of swing of the lever can be varied for adjustment purposes without interfering with the straight line motion of the pulleys carried by the lever.

The cable which I employ preferably has the strands thereof given a helical form before being assembled to form the cable. In this way each strand is freed from internal strains, and a cable so formed operates with a minimum of stretch or breakage and is therefore favorable to long life of the needle actuating mechanism.

It is a further object of my present invention to provide improved connections between the cable sections and the needle carriage so that the cable may be disconnected temporarily from the needle and its carriage for repair without danger that the cable will become unwrapped from the several pulleys.

With these and other objects in view which will appear as the description proceeds, my invention resides in the combination and arrangement of parts hereinafter described and set forth.

In the accompanying drawings, wherein a convenient embodiment of my invention is set forth:

Fig. 1 is a diagrammatic plan view of an Axminster loom showing the relation between the loom and needle operating mechanism with the needle in the shed.

Fig. 2 is a diagrammatic end elevation of part of an Axminster loom with the warp shed open to receive the needle, which is in section, looking in the direction of arrow 2, Fig. 1.

Fig. 3 shows a front elevation of my needle mechanism as it would appear at the right hand end of a loom with the needle in the shed, looking in the direction of arrow 3, Fig. 1.

Fig. 4 is a plan view looking in the direction of arrow 4, Fig. 3.

Figs. 5 and 6 are end elevations taken in the direction of arrows 5 and 6, respectively, Fig. 3.

Fig. 7 is an end elevation of the lever for operating the movable sheaves looking in the direction of arrow 7, Fig. 3.

Fig. 8 is a vertical section on line 8—8, Fig. 3.

Fig. 9 is a diagrammatic front elevation on a scale reduced from that of Fig. 3 and showing the movable sheave actuating mechanism in three different positions.

Fig. 10 is a detail of one end of the cable and its connector, showing the form of the wire strands of which the cable is composed.

Fig. 11 is a vertical section through the needle carriage on line 11—11, Fig. 3, on an enlarged scale.

Fig. 12 is a plan view looking in the direction of arrow 12, Fig. 11, showing also in dotted lines the means for holding the cable ends taut when disconnected from the needle carriage, and

Fig. 13 is an end elevation in the direction of arrow 13, Fig. 1.

Referring to the drawings, particularly Figs. 1 and 2, I have shown the frame 10 of an Axminster loom having a cloth board 11 over which the woven fabric F moves from the point of tuft

formation to a wind-up roll not shown. The binder warp threads B extend rearwardly from the cloth board through a reed R on a backwardly and forwardly reciprocating lay L. Harness frames H behind the lay shift vertically to divide the warp threads into top and bottom sheds S and S', respectively. The weft needle N is attached at its right end as seen in Fig. 5 to a carriage 12 which slides along a stationary needle rail 13 sufficiently long to accommodate the motion of the needle into and out of the warp shed.

The weft thread W is drawn from a stationary package 14 and threaded through an eye 15 at the left end of the needle and thence to the right hand selvage at 16. A selvage shuttle 17 having a selvage thread 18 attached to the left hand selvage at 19 is moved along a shuttle race 20 by an arm 21 secured to an oscillating vertical shaft 22 and passes between the two parts of the weft W which lead to the right from the eye 15.

The loom has a set of tube frames T three of which are shown in Fig. 2. These tube frames are successively moved to a delivery point under a pullover shaft 23 by two transporting chains one of which is shown at 24. The tube frame in delivery position is temporarily disconnected from the chains and lowered to tuft forming position by arms 25. The tuft yarns Y are projected downwardly through the warp sheds as shown in Fig. 2 to positions between the cloth board and the needle to the full line position of Fig. 2. The needle then lays a shot of weft and the reed beats up to force the weft and yarn tufts over the hooks 26 on the cloth board 11 to a position in front of the hooks. The tube frame is then raised to draw off enough yarn for the next row of tufts while the reed is held forward to prevent tuft slippage, and the harness frames shift to form a new shed. The front and back knives 27 and 28, respectively, then approach each other during the ensuing backward motion of the reed and start to cut at the left end of the loom as soon as the reed has moved far enough rearwardly to clear the back knife. Shortly thereafter the reed is back far enough to permit entry of the needle into the new shed which has been formed by the harnesses. The needle travels in the shed toward the left while the knives are still cutting the yarns Y, and the cutting ordinarily continues until the needle is entirely in the shed.

As the needle moves out of the shed the reed starts forward, cutting having been completed and the rear knife having moved back far enough to clear the advancing reed. The needle moves into and out of each warp shed and has a complete reciprocation for each backward stroke of the lay while the warp threads are spread apart to form a shed. The harnesses form a new shed for each reciprocation of the needle.

The matter thus far described is of common construction and may be constructed and operated as is customary in Axminster looms.

The loom to which my invention is applied has extending therefrom a floor plate 30 on which is supported an end frame 31 bolted to the loom frame. Fastened to the end frame is an upright bracket 32 to which the inner end of the needle rail 13 is secured. The rail comprises top and bottom bars 33 and 34, respectively, which are secured to an angle bar 35 fastened to the bracket 32. The adjacent faces 36 of the bars are oblique to form a dovetail slot which receives guide shoe 37 on the needle carriage 12. The right end of

the needle rail as seen in Figs. 3 and 4, is secured to a second vertical bracket 38 mounted on a post 39 resting on the floor. The needle rail is thus held in fixed position with respect to the loom so that the needle may be guided along the reed when moving into and out of the warp shed. The needle rail and its mounting may be of the usual construction but enters into one feature of my invention as will be pointed out hereinafter.

The frame 31 supports a shaft 40 which in the present instance rotates once in three beats of the loom. This shaft is secured to a driving spur gear 41 driven by means not shown and also has fastened thereto a bevel gear 42 having an uninterrupted series of teeth around its periphery which mesh with a bevel pinion 43 also having a continuous series of teeth and secured to a cross shaft 44 suitably supported. The latter therefore rotates continuously and preferably with a uniform rate of motion, and completes a rotation for each beat of the loom. Secured to shaft 44 is a crank arm 45 pivoted as at 46 to a driving connector 47.

Fastened to frame 31 is a bearing bracket 50 for a depending link 51 pivoted thereto at 52. The lower end of link 51 is pivoted on a stud 53 to which the right hand end of link 47 is also pivoted. Stud 53 is supported by a floating lever 54 to the upper end of which is secured a sheave pin 55 for a purpose to be described. Stud 53 is preferably equidistant from pivot 52 and pin 55.

As shown in Figs. 3 and 7, a bearing foot 56 has a vertical extension 57 extending along the lower end 58 of lever 54. A key 59 on extension 57 fits into a slot 60 in the lever end 58, and slots 61 in lever 54 receive bolts 62 to fasten the lever to the foot and afford vertical relative adjustment of the last named parts. The bearing foot receives a stud 63 supported by a link 64 the left end of which as viewed in Fig. 3 is pivoted at 65 to a bearing 66 secured to floor plate 30. Lever 54 therefore floats on links 51 and 64 and I am able to vary the stroke of its upper end and pin 55 by altering foot 56 relatively to the lever. Whatever the adjustment, however, stud 55 moves in an approximately straight horizontal line because of the proportions already described.

The bracket 38, as shown in Figs. 4 and 6, has a horizontal foot 70 resting on post 39 and formed with a vertical end 71 to which is bolted the outer end of a steel channel beam 72 the inner end of which is bolted to the front end of bracket 32, as at 73, as shown in Fig. 5. The needle rail, brackets 32 and 38, and the channel bar 72 therefore form a rigid rectangular frame on which are supported the fixed pulleys to be described.

Bracket 32 has a vertical horn 75 in which is slidably mounted a rod 76 the inner or left end of which as seen in Fig. 3 is surrounded by a compression spring 77 confined between the horn 75 and an adjusting nut 78 threaded on the rod. A rod head 79 on the rod is pivoted to a cable terminal 80 which is normally urged to the left, Fig. 3, by spring 77. Bracket 38 has a horn 81 through which extends a threaded rod 82 held in fixed adjusted position on the horn 81 by nuts 83, and a rod head 85 on rod 82 is pivoted to a cable terminal 86.

The cable terminals are connected to the ends of a cable, designated generally at C, which is trained around stationary and movable pulleys to be described. The cable is made of a plurality of steel wire strands 87, see Fig. 10, which extend into and are held to the terminals in any approved manner. The separate strands are given

a helical form as indicated in Fig. 10 before they are wrapped together to form the cable. In this way the strands and the cable formed of them are free from resilience which would tend to project them beyond the outline of the cable in case of breakage. Such a cable is subject to minimum breakage of the strands and has been found to have long life in actual use.

I will now describe the pulleys and the manner in which the cable is trained around them. The cable C could be continuous from one end to the other, but it is preferably formed of two sections C' and C2 which are largely at the left and right, respectively of lever 54 as viewed in Figs. 3 and 4.

Assuming the parts to be as shown in Fig. 3, and starting at the left, the cable C' extends from terminal 80 to and partly around movable pulley 90 on stud 55, see Fig. 4, and then leads to the left to a fixed pulley 91 of larger diameter than pulley 90 and rotatable in a yoked bearing 92 having a threaded shank 93 held adjustably in bracket 32 by nuts 94. Pulley 91 is inclined slightly upwardly and rearwardly as shown in Fig. 5, the bottom of pulley 91 being aligned with the bottom of pulley 90. The top of pulley 91 is aligned with the top of pulley 95 on stud 55, to which the cable C' next extends. Leaving the bottom of pulley 95 the cable is led to the bottom of another stationary pulley 96 rotatable on a yoked bearing 97 the shank 98 of which is held adjustably on bracket 32 by nuts 99. Pulley 96 is inclined upwardly and rearwardly more than is pulley 91, and is of greater diameter so that the bottom of pulley 96 is aligned with the bottom of pulley 95 while the top thereof is aligned with the top of movable pulley 100 on stud 55. From the bottom of pulley 100 the cable C' extends to the bottom of pulley 101 rotatable on stud 102 fixed to bracket 32, and then leads to a terminal 103 connected to the needle carriage at 105.

All the movable pulleys are of substantially the same thickness, and from Fig. 4 it will be seen that the strain toward the left exerted on stud 55 by pulleys 90 and 95, which are in positions one and two, respectively, in front of lever 54, is balanced by the pull to the left of pulley 100, which is in position three relatively to the lever and behind the latter. There is therefore little or no twisting of stud 55 and lever 54 because of the different distances of these pulleys from the lever. The inclination of the stationary pulleys not only allow the various sections of the cable C' to leave the pulleys without tendency to slip off them, but also permits the balancing of forces as described.

The other half C2 of the cable is similar to the part C' and cooperates with a set of pulleys like those already set forth. From terminal 106 connected to the needle carriage at 106, cable section C2 leads to the top of stationary pulley 109 rotatable on a stud supported by bracket 38 at the outer or right hand end of the needle rail as seen in Figs. 3 and 4. The plane of pulley 101 is vertical, since it receives section C' from the rearmost movable pulley 100 aligned with it, but pulley 109 is slightly oblique, see Fig. 6, to permit cable C2, when leaving the bottom of pulley 109, to extend to the bottom of movable pulley 110 on stud 55 immediately in front of pulley 100 along a line substantially parallel to the plane of pulley 110. Cable section C2 then leads to inclined stationary pulley 111 rotating on a yoked bearing 112 threaded into bracket 38 and held in adjusted position by nuts 113. From

the bottom of pulley 111 the cable C2 leads to the bottom of movable pulley 114 just behind lever 54 on stud 55 and is then led to stationary pulley 115 rotatable on a bearing 116 similar in construction and mounting to part 112. Pulley 115 is inclined considerably, similar to pulley 96, but of larger diameter, so that its top aligns with the top of pulley 114 and its bottom with the bottom of movable pulley 117 to which cable C2 extends. Pulley 117 is the front most pulley on stud 55 and cable C2 leads from it to the previously described terminal 86. All the pulleys are grooved as suggested in Figs. 5 and 6, and the cables lead to the pulleys in the planes of the pulleys and their flanges. As with cable section C', section C2 extends around the movable pulleys in such a way as to balance the strains on stud 55 and there is no appreciable tendency to twist lever 54.

In operation, and assuming that shaft 44 rotates uniformly as indicated by arrow *a*, Fig. 3, and that the parts are in the position shown in Fig. 3 with the needle in the shed, corresponding to the dot and dash position of Fig. 9, the lever 54 will rock to the left by counter-clockwise rotation of shaft 44, and in doing so will carry the six movable pulleys which rotate on the stud 55. As these pulleys move to the left the distance between stud 55 and the fixed pulleys at the left of the mechanism decreases to shorten the length of that part of cable section C' extending to the left from pulleys 90, 95 and 100. At the same time the length of cable C2 extending to the right from pulleys 110, 114 and 117 to the stationary right hand pulleys will increase. The increase at the right is compensated for by the shortening at the left, and that part of the cable extending between the large fixed pulleys 101 and 109 therefore moves to the right and carries the needle carriage toward the pulley 109 to retract the needle from the shed.

During motion to the left, lever 54 will pass from the dot and dash position of Fig. 9 through the full line position, at which time the needle is moving at its most rapid rate, and then passes on to the dotted position at the left of Fig. 9 which corresponds to the end of the needle retracting stroke. The harnesses H will then change and the lay will beat up the weft laid by the needle.

As shaft 44 continues to rotate lever 54 will start to move to the right and in doing so will cause the cable to have motion the reverse of that already described to move the needle carriage to the left to insert the needle in the new shed. This complete reciprocation of the needle occurs once for each beatup of the lay and change of the harnesses.

I have found that a needle motion constructed as set forth herein can be operated at a higher rate of speed than motions heretofore constructed due to the fact that the cable and movable pulleys are comparatively light. I have shown six movable pulleys, three for inserting and three for retracting the needle, and since each movable pulley either slackens or takes up, depending upon the direction of its motion, twice as much cable as the distance through which it moves, I am able to drive the needle through a distance six times the length of travel of stud 55 in a horizontal direction. It is the horizontal motion of stud 55 which is effective in causing movement of the cable, and it is for this reason that I use the suspension link 51 which in effect causes the stud 55 to move in a substantially horizontal line with no vertical motion which would be useless

in causing needle movement. I find also that by making the pulleys of a composition material, such as a phenol-condensation product, they can be made thin and at the same time withstand wear as the cable moves along their grooves.

During the operation of the needle motion the cable sections C' and C2 are placed under tension alternately to move the needle into and out of the shed, respectively. When lever 54 starts its motion to the right from the dotted line position of Fig. 9 the needle is momentarily at rest out of the shed, but the spring 77 will be under an initial compression sufficient to hold the cable sections taut. This initial compression is sufficient to withstand the strain necessary to overcome the inertia of the needle and its carriage during the first part of the insertion stroke. As lever 54 reaches the full line position of Fig. 9, however, the needle is accelerating at its fastest rate and the pull exerted by cable section C' on the rod 76 is likely to cause a slight further compression of spring 77. The spring will yield only a small amount, however, and any accompanying slackness in the section C2 will not be enough to permit the cable to slip out of the grooves of the pulleys it engages. As the lever 54 moves from the full line to the dot and dash line position in Fig. 9 its motion is retarded, but the needle tends by its momentum to run ahead of the lever, thereby setting up an additional tension in section C2. An inspection of Fig. 1 will show, however, that it is necessary to have the needle eye 15 properly located with respect to the shuttle 17 and in order to effect this relationship the cable section C2 is rigidly anchored by means of the rod 82, the additional tension in section C' not materially affecting the location of the needle eye. On the reverse or retracting stroke it is desirable to get the needle out of the shed as quickly as possible, and this result will be accomplished, since there will be no yielding of the anchor of cable section C2 when the needle acceleration approaches or reaches its maximum acceleration. When the needle tends to override lever 54 while moving out of the shed the spring 77 can yield, inasmuch as it is not necessary for the needle to register with any other mechanism, such as shuttle 17, when out of the shed. It is to be understood that the shuttle 17 loops its selvage thread with the weft thread W laid by the needle in a very short time while the needle is accurately positioned for this operation. By having cable section C2 rigidly anchored I am able to place the needle correctly for cooperation with the shuttle 17. Experience has shown that a needle motion constructed as set forth herein permits almost unfailing cooperation between the shuttle 17 and the needle, and the so-called "slip shots," which have occurred rather frequently with Axminster needle mechanisms as heretofore constructed, practically never occur with my invention. The spring 77 furthermore serves the purpose of keeping the cable in close contact with the pulleys to prevent any appreciable slippage and as a result of this action of spring 77 wearing of both the cable and the pulleys is reduced to a minimum.

In order that the relation between the selvage shuttle and the weft needle may be understood in the description of the operation of the mechanism already given, reference may be had to Figs. 1 and 13. It is to be understood that the selvage shuttle 17 must have its operating movement when the needle is fully inserted into the

shed so that the selvage thread can pass through the weft loop carried by the needle. In order to provide for the correct timing of the selvage shuttle, the shaft 40, which extends entirely across the loom, carries a cam 29 having three spaced cam points 48. These points cooperate with a lever 49 the upper end of which is attached by means of a connector 67 to a lever 68 secured to the lower part of shaft 22. During operation of the loom shaft 40 makes a 10 rotation every third beat of the lay, but the three cam points 48 cause the shuttle to have an operating motion every beat of the loom. The setting of the cam 29 on shaft 40 is such that shaft 22 oscillates when the needle is at or near the end of its stroke into the warp shed. The selvage shuttle operating mechanism may be of the usual type but the timing of its operation is closely related to the movement of the movable pulleys and occurs when the latter are at or near their extreme right hand positions shown in dot and dash lines, Fig. 9.

On the weft needle inserting stroke the final position of the needle is determined by cable section C2 and its anchor 82, since it is this section of the cable which holds the needle back, while the other section C' is moving it into the shed. The shuttle actually moves in two stages the first of which passes the advancing nose 69 through the welt loop while the needle is fully inserted in the shed, and the needle is then started on its outward motion, after which the shuttle has its second movement and passes completely through the loop of weft. The anchor 82 serves very effectively to insure accurate registry and rapid start of the needle away from the shuttle.

It is occasionally necessary to repair the needle or the needle carriage, an operation which ordinarily requires removal of these parts from the loom, and under these conditions it is desirable that the cables be maintained in their normal position with respect to the sheaves so that it will be unnecessary to fit the cables to the sheaves after the needle and its carriage have been reinserted in the loom. In order to carry this feature of my invention into effect I provide the structure shown in detail in Figs. 11 and 12, where the carriage 12 is shown as having an angular shoe 37 into which the needle end is fitted. This shoe slides between the needle rail bars 33 and 34, and projecting forwardly from it is a lug 126 into which are threaded the screws 105 and 106 for the cable terminals 103 and 108, respectively. Each of these screws is threaded into the lug 126 and has a shoulder bearing section 127 which passes through the corresponding cable terminal and also through a link 128. This link has a close fit with the section 127, hence a strain in one of the cable sections tending to move the carriage 12 in one direction would be communicated to the screw for the terminal of the other cable section. In this way both of the screws 105 and 106 are required to assist in transmitting a force from either of the cable sections to the needle carriage.

Should it be necessary to repair either the needle or the carriage, the screws 105 and 106 can be disconnected from the lug 126 but kept in contact with their respective terminals 103 and 108 and remain connected together by the link 128. This relation, shown in dotted lines at the bottom of Fig. 12, serves to maintain the cable sections properly trained around their sheaves while disconnected from the needle and

its carriage. The spring 11 will exert sufficient pull on the two sections to hold the parts together in the dotted line position shown in Fig. 12, and after the needle and its carriage have been repaired and restored to the loom, the structure can be reassembled as shown in full lines in Fig. 12 without the necessity of training the cable around the several pulleys.

From the foregoing it will be seen that I have provided a simple form of needle actuating mechanism for an Axminster loom including stationary and movable pulleys which cooperate with a flexible cable connected to the needle carriage in such a way that motion of the movable pulleys causes the carriage to move along the needle rail. The actuating mechanism is light and the needle can therefore be moved into and out of the shed for each beat of the loom, thereby permitting the attainment of high speeds in Axminster looms. The fact that a permanent connection exists between the needle and the needle carriage, rendering unnecessary any disconnection between these parts under normal operation, is an important factor in contributing to the success of my invention. It will further be seen that wearing of the different parts of the mechanism is uniform and that both the sections C' and C2 can be made of substantially the same size cable due to the fact that the strain of inserting the needle is substantially the same as that required for its retraction. Also, the spring 11 places the cable under an initial strain which holds it against the cables to prevent slippage, thus avoiding wear. The spring is also of use in permitting a small amount of yielding when the needle has reached its highest rate of acceleration during insertion into the shed, and also when the needle tends to override the lever 54 after reaching its maximum speed. The normal tension exerted by the spring holds the ends of the cable sections remote from the needle carriage in substantially fixed relative position. The fixed anchorage for cable section C2 determines accurately the location of the needle eye 15 with respect to the selvage shuttle 17. The diagonal stationary sheaves make possible the alignment of the various sections of the cable with the planes of the movable pulleys with which they cooperate and there is little or no wear of the flanges of the pulleys. The pre-formed wire is also a significant feature of my invention in that the cable is practically free from internal strains and there is a minimum tendency for the individual strands of the cable to break, or project beyond the outline of the cable should they break. It will further be noted that the needle rail is part of a rectangular frame which supports the stationary pulleys, this feature being possible due to the fact that the needle rail is stationary. The link suspension of the lever 54 permits the movable pulleys to move in a horizontal line toward and from the fixed pulleys. Another feature of my invention is found in the fact that the cable section C', for instance, is trained around three of the movable pulleys in such a way that the combined strain transmitted to the lever 54 from two of the sheaves is balanced by the strain transmitted to the lever through the third sheave, thus avoiding distortion of the lever. A further feature of my invention of practical operating importance is the fact that the link which connects the terminal attaching screws 105 and 106 serves to maintain the cable trained around the sheaves when

it is temporarily disconnected from the needle carriage.

It will also be noted that the selvage shuttle mechanism is timed with lever 54 so that the cam points 48 rock shaft 22 to cause an inter-looping of the selvage thread with respect to the weft laid by the needle each time the movable pulleys are near their right hand or outermost position shown in dot and dash lines in Fig. 9.

Having thus described my invention it will be seen that changes and modifications may be made therein by those skilled in the art without departing from the spirit and scope of the invention and I do not wish to be limited to the details herein disclosed, but what I claim is:

1. In a weft needle operating mechanism for a loom, a needle rail, a needle carriage to slide along the rail, a cable having an intermediate part thereof attached to the carrier, means to hold one end of the cable fixed, spaced stationary pulleys around which extend the parts of the cable leading from the carriage, a set of movable pulleys, the cable having parts extending from the stationary pulleys to and around the movable pulleys, means to reciprocate the set of movable pulleys in a direction toward and from the stationary pulleys to cause the carriage to reciprocate along the rail, and yielding means to anchor the other end of the cable, said yielding means normally maintaining tension in the cable to hold the latter constantly in close contact with the pulleys.

2. In a weft needle operating mechanism for an Axminster loom having a needle rail and a needle carriage to be reciprocated along the rail to move a needle into and out of a warp shed, a cable having an intermediate part thereof attached to the carriage, spaced stationary pulleys around which extend the parts of the cable leading from the carriage, a set of movable pulleys located between the stationary pulleys, the cable having parts extending from the stationary pulleys to and around the movable pulleys, means to reciprocate the set of movable pulleys in a direction toward and from the stationary pulleys to cause the carriage to move the needle into the shed and tension one end of the cable when said movable pulleys move in one direction and move the carriage to retract the needle from the shed and tension the other end of the cable when said movable pulleys move in the other direction, means to hold said one end of the cable fixed, and yielding means attached to the other end of the cable to preserve a normal tension in the cable greater than the tension set up in the cable at the beginning of a motion of the needle carriage along the needle rail.

3. In a weft needle operating mechanism for an Axminster loom having a needle rail and a needle carriage to reciprocate along the rail to move a weft needle into and out of a warp shed, a cable having an intermediate part thereof attached to the carriage and having one end thereof fixed, spaced stationary pulleys around which extend parts of a cable leading from the carriage, a set of movable pulleys, the cable having parts thereof extending from the stationary pulleys to and around the movable pulleys, means to reciprocate the set of movable pulleys in unison in a direction toward and from the stationary pulleys to cause the carriage to move toward the warp shed when said movable pulleys move in one direction and cause said carriage to move away from the warp shed when the movable pulleys move in the opposite direction, and yielding

means connected to the other end of the cable to maintain a tension on the cable, said movable pulleys to tension that part of the cable the end of which is fixed when the carriage moves away from the warp shed and said movable pulleys to tension the other part of the cable the end of which is attached to said yielding means when the carriage moves toward the warp shed.

4. In a weft needle operating mechanism for an Axminster loom having a needle rail and a needle carriage to reciprocate along the rail to move a weft needle into and out of a warp shed, a cable having an intermediate part thereof attached to the carriage and having one end thereof fixed, spaced stationary pulleys around which extend parts of a cable leading from the carriage, a set of movable pulleys, the cable having parts thereof extending from the stationary pulleys to and around the movable pulleys, means to reciprocate the set of movable pulleys in unison in a direction toward and from the stationary pulleys to cause the carriage to move toward the warp shed when said movable pulleys move in one direction and cause said carriage to move away from the warp shed when the movable pulleys move in the opposite direction, and yielding means connected to the other end of the cable to maintain a tension on the cable, that part of the cable which is drawn after the carriage when the latter moves toward the shed having the end thereof fixed and that part of the cable which is drawn after the carriage when the latter moves away from the shed having the end thereof attached to said yielding means.

5. In a weft needle operating mechanism for a loom, a needle rail, a needle carriage to slide along the rail, a weft needle secured at one end to the carriage and having a weft receiving eye in the other end thereof opposite to the carriage, a cable having an intermediate part thereof attached to the carriage and having the ends thereof substantially fixed with respect to each other, spaced stationary pulleys around which extend the parts of the cable leading from the carriage, a set of movable pulleys, the cable having parts extending from the stationary pulleys to and around the movable pulleys, and means to reciprocate the movable pulleys in unison in a direction toward and from the stationary pulleys to cause the carriage to reciprocate along the rail, said cable formed of a plurality of metallic strands each having a normal spiral form.

6. In a weft needle operating mechanism for a loom, a needle rail, a needle carriage to slide along the rail, a cable having the intermediate parts thereof attached to the carriage and having the ends thereof substantially fixed with respect to each other, spaced stationary pulleys around which extend the parts of the cable leading from the carriage, a set of movable pulleys, both the stationary and movable pulleys being formed of a phenol condensation product, the cable having parts extending from the stationary pulleys to and around the movable pulleys, and means to reciprocate the movable pulleys in unison in a direction toward and from the stationary pulleys to cause the carriage to reciprocate along the rail, said cable formed of several pre-formed wire strands each of which in its normal condition is of spiral form the several strands thus normally formed being combined to form the cable.

7. In a weft needle operating mechanism for an Axminster loom having a needle rail and a needle carriage to be reciprocated therealong,

a cable formed of two sections the ends of which remote from the carriage are substantially fixed with respect to each other, a system of stationary and movable pulleys around which the cable sections are trained to effect movement of the needle carriage along the needle rail by movement of the movable pulleys in the system, a link between the other ends of the cable sections, and attaching means extending through the link to connect said other ends of the cable sections to the needle carriage, said link capable of transmitting a driving force derived from the cable to the needle carriage through the attaching means.

8. In a weft needle operating mechanism for an Axminster loom having a needle rail and a needle carriage to be reciprocated therealong, a cable formed of two sections the ends of which remote from the carriage are substantially fixed with respect to each other, a system of stationary and movable pulleys around which the cable sections are trained to effect movement of the needle carriage along the needle rail by movement of the movable pulleys in the system, and attaching means normally connected to the carriage and connecting the cable sections together and transmitting driving force from the cable sections to the needle carriage and detachable from the carriage while maintaining the cable sections connected together.

9. In a weft needle operating mechanism for an Axminster loom having a needle rail and a needle carriage to be reciprocated therealong, a cable formed of two sections the ends of which remote from the cable carriage are substantially fixed with respect to each other, a system of stationary and movable pulleys around which the cable sections are trained to effect movement of the needle carriage along the needle rail by movement of the movable pulleys, a link between the other end of the cable sections, a pair of spaced attaching means extending through the link and having holding connection with the needle carriage, said attaching means being connected each to one of said other ends of the cable sections, said link serving to hold said other ends of the cable sections in normal position when said attaching means are disconnected from the needle carriage.

10. In a weft needle operating mechanism for an Axminster loom having a needle rail and a needle carriage to be reciprocated therealong, a cable formed of two sections, the end of one of said sections remote from the cable carriage being fixed, a system of stationary and movable pulleys around which the cable sections are trained to effect movement of the needle carriage along the needle rail by movement of the movable pulleys, means normally connected to the carriage and connecting the cable sections together and transmitting driving force from the cable sections to the needle carriage, said attaching means being detachable from the needle carriage while maintaining the cable sections connected together, and resilient means acting on the end of the other cable section remote from the needle carriage to assist in maintaining the holding connection between said attaching means and the ends of the cable sections connected thereto.

11. In a weft needle mechanism for an Axminster loom having on one side thereof a needle rail along which a needle carriage and a weft needle permanently connected to the carriage make a complete reciprocation for each of a se-

ries of regularly recurring successive loom beats, a selvage shuttle on the other side of the loom to cooperate with the weft of the needle when the latter is in the warp shed, a stranded wire cable having an intermediate part thereof connected to the needle carriage and having the ends thereof substantially fixed with respect to each other, spaced stationary pulleys around which extend the parts of the cable leading from the needle carriage, a set of movable pulleys, support means for the movable pulleys to cause the latter when moved to travel in a straight line extending between the stationary pulleys, the cable having parts thereof extending from the stationary pulleys to and around the movable pulleys, an operating member having a complete movement for each beat of the loom, connections between the member and the set of movable pulleys to give the latter a complete reciprocating movement in unison relatively to the stationary pulleys once for each beat of the loom, thereby causing the needle to move into and out of the warp shed on each beat of the loom, and means connected to the member to give the selvage shuttle an operating movement when the movable pulleys have been moved by the member to that end of their motion which moves the needle into the shed.

12. In a weft needle mechanism for an Axminster loom having on one side thereof a needle rail along which a needle carriage and a weft laying needle connected to the carriage make a complete reciprocation for each of a series of regularly recurring successive loom beats, a selvage shuttle on the other side of the loom to cooperate with the weft of the needle when the latter is completely in the warp shed, a stranded wire cable having an intermediate part thereof connected to the needle carriage and having the ends thereof substantially fixed with respect to each other, spaced stationary pulleys around which extend the parts of the cable leading from the needle carriage, a set of movable pulleys, support means for the movable pulleys to cause the latter when moved to travel in a straight line extending between the stationary pulleys, the cable having parts thereof extending from the stationary pulleys to and around the movable pulleys, a shaft extending across the loom, shuttle driving means operated by the shaft to give the selvage shuttle an operating motion for each beat of the loom, and pulley driving means operated by the shaft to give the movable pulleys a complete reciprocating movement in unison once for each beat of the loom to cause the needle to move into and out of the warp sheds once for each beat of the loom, the shuttle driving means operated by the shaft causing said selvage shuttle to have an operating movement with respect to the weft of the needle when said shaft has operated the pulley driving means substantially to complete movement of the movable pulleys on that part of their reciprocating movement which inserts the needle into the warp shed.

13. In a weft needle mechanism for an Axminster loom having on one side thereof a needle rail along which a needle carriage and a weft laying needle connected to the carriage make a complete reciprocation for each of a series of regularly recurring successive loom beats, a selvage shuttle on the other side of the loom to cooperate with the weft of the needle when the latter is completely in the warp shed, a stranded wire cable having an intermediate part thereof connected to the needle carriage and

having the ends thereof substantially fixed with respect to each other, spaced stationary pulleys around which extend the parts of the cable leading from the needle carriage, a set of movable pulleys, support means for the movable pulleys to cause the latter when moved to travel in a straight line extending between the stationary pulleys, the cable having parts thereof extending from the stationary pulleys to and around the movable pulleys, an operating shaft extending across the loom, connections between the shaft and the selvage shuttle to cause the latter to have an operating motion each beat of the loom when the weft needle is fully inserted into the warp shed, and other connections between the shaft and the movable pulleys to give the latter a complete reciprocating movement in unison for each beat of the loom to cause the needle to move into and out of the warp sheds on each beat of the loom, said other connections acting to move the movable pulleys to an extreme position at substantially the same time that the first named connections give the selvage shuttle an operating movement, said extreme movement of the movable pulleys being that corresponding to the position of the needle when the latter is fully inserted into the warp shed.

14. In a weft needle mechanism for an Axminster loom having on one side thereof a needle rail along which a needle carriage and a weft laying needle connected to the carriage make a complete reciprocation for each of a series of regularly recurring successive loom beats, a selvage shuttle on the other side of the loom to cooperate with the weft of the needle when the latter is completely in the warp shed, a stranded wire cable having an intermediate part thereof connected to the needle carriage and having the ends thereof substantially fixed with respect to each other, spaced stationary pulleys around which extend the parts of the cable leading from the needle carriage, a set of movable pulleys, the cable having parts thereof extending from the stationary pulleys to and around the movable pulleys, a single actuator for the selvage shuttle and the movable pulleys, means connecting said actuator to the selvage shuttle to give

5 the latter an operating movement each beat of the loom, and other means connecting said actuator to the movable pulleys to give the latter a movement to cause motion of the weft needle into the warp shed which is completed at substantially the same time that the first named means gives said selvage shuttle an operating movement.

15. In a weft needle mechanism for an Axminster loom having on one side thereof a needle rail along which a needle carriage and a weft laying needle connected to the carriage make a complete reciprocation for each of a series of regularly recurring successive loom beats, a selvage shuttle on the other side of the loom to cooperate with the weft of the needle when the latter is completely in the warp shed, a stranded wire cable having an intermediate part thereof connected to the needle carriage and having the ends thereof substantially fixed with respect to each other, spaced stationary pulleys around which extend the parts of the cable leading from the needle carriage, a set of movable pulleys, the cable having parts thereof extending from the stationary pulleys to and around the movable pulleys, means to hold in fixed position that end of the cable which follows the needle carriage when the latter is moving to insert the needle into the warp shed, a common actuator for the selvage shuttle and the movable pulleys, mechanism operated by said actuator to give the selvage shuttle an operating movement when the weft needle is completely inserted into the warp shed and positioned for cooperation with the selvage shuttle by said fixed end of the cable, and other means connecting the actuator to the movable pulleys to cause the latter to have a complete reciprocation in unison for each beat of the loom to cause the needle to move into and out of a warp shed on each beat of the loom, the first named means operative to give the selvage shuttle its operating movement when the second named means has substantially completed that movement of the movable pulleys corresponding to the insertion of the needle in the warp shed.
